Term of patent 14 years

(Cl. D33—14)

FIG. 2.

FIG. 1.

Fig. 6.

FIGURE 1 is a front elevational view of a table showing my new design;

FIGURE 2 is a top plan view thereof;

FIGURE 3 is an elevational view of one side thereof taken from the left;

FIGURE 4 is an elevational view taken from the other side thereof;

FIGURE 5 is an elevational view taken from the rear thereof, and

FIGURE 6 is a perspective view thereover.

The dominant features of my design reside in those portions shown in full lines on the drawing.

I claim:

The ornamental design for a table, substantially as shown and described.
